CLAIM

The ornamental design for an end configuration for seating furniture, as shown and described.

DESCRIPTION

FIG. 1 is an isometric view of an end section for seating furniture incorporating my new design,

FIG. 2 is a front elevation view thereof;

FIG. 3 is a side elevation view thereof;

FIG. 4 is a top plan view thereof;

FIG. 5 is a rear elevation view thereof;

FIG. 6 is an isometric view of another embodiment of an end section for seating furniture incorporating my new design, and wherein the side elevation is the same as FIG. 3;

FIG. 7 is a front elevation view thereof;

FIG. 8 is a top plan view thereof;

FIG. 9 is a rear elevation view thereof;

FIG. 10 is an isometric view of another embodiment of an end section for seating furniture incorporating my new design, and wherein the side elevation is the same as FIG. 3;

FIG. 11 is a front elevation view thereof;

FIG. 12 is a top plan view thereof; and,

FIG. 13 is a rear elevation view thereof.
